COIN CONTROLLED METERING DEVICE

George H. Niederst, Chicago, Ill., assignor, by
mesne assignments, to International-Register
Company, Chicago, Ill., a corporation of Illi-
nois

Application February 3, 1936, Serial No. 62,009

7 Claims. (Cl. 200—33)

The present invention relates to coin controlled metering devices, and is particularly concerned with a metering device which is adapted to be used with refrigerators or other domestic 5 appliances.

One of the objects of the invention is the provision of an improved metering device of the class described which is adapted to permit defrosting at any time desired by the operator and 10 which is also adapted to provide for the automatic defrosting of the refrigerator.

Another object of the invention is the provision of an improved coin controlled device of the class described which includes a timing ele- 15 ment which is adapted to run continuously, even when the domestic appliance has been shut off by the coin controlled device.

Another object of the invention is the provision of a coin controlled device of the class de- 20 scribed in which the mechanism is adapted to ready modification for the purpose of predeter- 15 mining the period of operation of any device for the deposit of a coin.

Another object of the invention is the provision 25 of a coin controlled device for refrigerators which defrosts automatically every twenty-four hours or which may be defrosted selectively at any time and in which the operator can predetermine the next period of defrosting.

Another object of the invention is the provision 30 of an improved construction for coin controlled devices in which there is a marked reduction in the number of dies required for man- 35 ufacture and in the number of gears, and there- fore a reduction in the cost of the manufacture of the device.

Another object of the invention is the provision 40 of an improved coin controlled device which is sturdy, efficient, economical and capable of ad- 45 justment and modification to take care of a wide variety of different conditions, particularly in the period of time of operation of the controlled device for any coin deposited.

Other objects and advantages of the invention 45 will be apparent from the following description and the accompanying drawings, in which similar characters of reference indicate similar parts throughout the several views.

Referring to the three sheets of drawings, 50 Fig. 1 is a fragmentary view in perspective of a refrigerator equipped with a coin controlled device constructed according to the present invention;

Fig. 2 is a wiring diagram of the controlling 55 device;

Fig. 3 is a sectional view, partially broken away to show the construction of the switch actuating mechanism;

Fig. 4 is a top plan view, with the casing in section, on the plane of the lines 4—4 of Fig. 5; 5

Fig. 5 is a front elevational view of the mechanism of the device, with the casing in section;

Fig. 6 is a vertical sectional view, taken on the plane of the line 6—6 of Fig. 5, looking in the direction of the arrows; 10

Fig. 7 is a sectional view, taken on the plane of the line 7—7 of Fig. 6, showing the positive coin actuating means;

Fig. 8 is a sectional view of the mechanism, taken on the plane of the line 8—8 of Fig. 5, 15 looking in the direction of the arrows.

Referring to Figs. 1 and 2, 10 indicates in its entirety the electric refrigerator, which is controlled by the coin controlled device 11, located on the top of the refrigerator or some other 20 convenient point.

The wiring diagram shown in Fig. 2 shows that the refrigerator 10, which derives its power supply through the power lines 12 and 13, is controlled by a switch comprising a movable arm 14 25 and a fixed contact 15 actuated by a cam 16.

The timing device or clock motor 17 is placed directly across the line 12, 13, and therefore operates continuously. This is preferably a constant speed motor of the self-starting type, but 30 synchronous or non-synchronous clock motors may be used, and where an accurate clock motor is used the clock may be provided with an exposed dial so that the coin controlled device serves the purpose of a clock as well as a controlling 35 device.

The constant speed motors which will be used in the more simple embodiments of the invention are preferably not used as clocks for the reason that while these motors are of sufficiently constant speed to determine the time interval for operation of the refrigerator, they are not sufficiently accurate to check with modern synchronous clocks, and might therefore be subjected to criticism if used as clocks. 40

The switch 14, 15 may consist of a push button 18 which controls what is usually known as a micro-switch, and which comprises a snap switch of the type having a movable spring arm 14 with a preformed depression which causes the arm to snap out of engagement with the fixed contact 15 when the arm is moved a predetermined amount. 45

A stronger spring 19 (Fig. 2) urges the arm into engagement with the contact 15 when the 55

ing sleeve 63, which slidably and rotatably supports a stub shaft 64 in alignment with the stub shaft 48 when the housing is in proper position. Shaft 64 carries a radially projecting arm 65 which is adapted to clear the projecting rivets or lugs 66 on the dial plate 56 when the shaft 64 is in the position of Fig. 6. The shaft is held in this position by a compression coil spring 67, which is compressed between the end of the bushing 63 and the hand knob 68 that is fixedly mounted on shaft 64.

When the operator wishes to turn the dial plate 56, he has only to push in on the knob 68 and simultaneously turn the knob, whereupon the arm 65 will engage one of the rivets or lugs 66, and shaft 64 will carry along with it in its rotation the dial plate 56. Any number of lugs 66 may be used, so that the knob 68 may be used to turn the dial plate to any desired position. Thus the dial may be turned until the defrosting indicator is shown at the aperture 59, or it may be turned past the aperture 59 so as to predetermine the time when the next defrosting period will arrive.

The pins 54 of lantern wheel 49 are adapted to engage the camming flange 69 carried by a bell crank lever 70, which is pivotally mounted on a stud 71. Flange 69 is, of course, disposed at an angle to the direction of movement of pins 54, so that as the lantern wheel rotates in a clockwise direction pins 54 tend to actuate bell crank lever 70 in a clockwise direction until the pin passes the camming flange 69. Bell crank 70 carries the flange 69 on a short arm 72, and is provided with a downwardly extending arm 73, which carries a spring pawl 74.

The bell crank arm 73 is urged in a counter-clockwise direction by a tension spring 75, which has its opposite end secured to the frame, and the pawl 74 engages a ratchet wheel 76 which is rotatably mounted upon a fixed stud 71. Ratchet wheel 76 preferably has a multiplicity of teeth so as to be capable of arrangement with the pins on the lantern wheel to predetermine the length of time for operation of the device. For example, in this embodiment the ratchet wheel 76 has ten teeth. It is engaged by a spring pawl 78 which permits the rotation of the ratchet wheel 76 in a clockwise direction, but which resists counter-clockwise rotation.

The ratchet wheel 76 has certain of its teeth provided with laterally extending flanges 79 that are adapted to engage the teeth 80 of a ratchet wheel 81. Ratchet wheel 81 has its teeth arranged so that abrupt radial shoulders on the teeth 80 are engaged by the flanges 79, and when the ratchet wheel 76 is rotated a sufficient number of steps, one of the flanges 79 engages a tooth 80 and rotates the ratchet wheel 81 one step.

Ratchet wheel 81 is provided with a hub 82 about which is wound a coil spring 83, one end being secured to the frame at 84, and the other end of the coil spring being secured to hub 82. Coil spring 83 urges ratchet wheel 81 in a clockwise direction, but spring 75 is strong enough so that lever 73 and ratchet wheel 76 are adapted to rotate the ratchet wheel 81 against the tension of spring 83.

Ratchet wheel 81 also bears a dial plate or may be made in the form of a metal dial, with the numbers etched directly upon the metal, and the numbers 1 to 8, which appear in Fig. 5, are exemplary of figures which may be used to indicate the number of coins deposited in the device.

The housing 20 is provided with another aperture 85 disposed in its front wall opposite the numeral which appears uppermost on the dial plate 86 for the purpose of permitting the operator to see at any time what number of coins 5 has been deposited and has not yet been used up.

The escapement pawl takes up space for several teeth, and several teeth are cut out at 87.

In the present embodiment the ratchet wheel 81 has a plurality of teeth removed at the space 10 87 and is provided with thirty teeth, which permits the deposit and registration of twenty coins. After these twenty coins have been used up and the dial plate 86 has been rotated to a corresponding extent, the tooth cut-out portion 87 is 15 in such position that it registers with the flanges 79 on ratchet wheel 76, and no matter how often the ratchet wheel 76 is then actuated it can have no effect on rotation of ratchet wheel 81 because of the absence of the teeth at the point 87. 20 Thus the constant speed timing motor may operate continuously, and it may actuate the lantern wheel lever 70 and ratchet wheel 76, but the removal of teeth at 87 prevents ratchet wheel 81 from interfering with the operation of the 25 clock motor when no coins are registered on the coin registering dial 86.

The dial 86 is also provided with a camming flange 88 which is located at the zero position of the dial and extends peripherally a sufficient 30 distance so that it is adapted to engage the switch lever 58 when the dial is at the zero position.

The switch lever 58 is disposed between the two dials 56 and 86 in such position as to be actuated by the two camming flanges 57 and 88. It comprises a laterally extending portion 89 which is disposed substantially parallel to the plane of these dials, but which has a bent camming portion 90 that projects out in front of the plane 40 of the dials except when it is moved back by either of the camming members 57 or 88.

Switch lever 58 extends backward from the portion 89 and is pivotally mounted at 91 on a pair of laterally projecting ears carried by the 45 frame. It has a laterally projecting portion 92 which is adapted to engage the push button 18 of the microswitch.

When the parts are in the position of Fig. 3, the microswitch is closed, but when either of 50 the camming flanges 57 or 88 rests in front of the bend 90, the portion 92 of switch lever 58 moves clockwise in Fig. 3, to actuate the push button 18 and open the microswitch 14, 15. A releasing pawl 43 is pivotally mounted on the 55 frame at 93 adjacent the ratchet wheel 81. It is provided with a pair of teeth 94, 95, one of which is always in engagement with the teeth of ratchet wheel 81.

Pawl 43 is urged in a counter-clockwise direction by a spring 96, tending to maintain the tooth 94 in engagement with the ratchet wheel 81. The lever 38, which is actuated by a coin 36, has a laterally projecting portion 97 with a camming surface 98 for engaging the end of 60 escapement pawl 43. When lever 38 is urged in a clockwise direction (Fig. 6) by the passage of a coin 36, its camming portion 98 slides against the end of escapement pawl 43 and rotates this pawl in a clockwise direction. This causes tooth 70 95 to enter the space between two of the teeth on the ratchet wheel 81, and as the tooth 94 comes out of engagement with the ratchet wheel 81 the ratchet wheel is held by tooth 95. When the coin has passed and lever 38 again moves, 75

counter-pawl 43 again moves upward and tooth 94 engages the ratchet wheel 81. Thus the passage of the coin causes the escapement pawl 43 to permit the ratchet wheel 81 to rotate one step in a clockwise direction. This brings the numerals on the dial 86 into registry with the aperture 85, a suitable numeral indicating how many steps the ratchet wheel 81 has moved in its registry of the coins.

10 The ratchet wheel 81 and dial 86 are thus moved step by step in a clockwise direction, when coins are deposited, and as the coins are used up this ratchet wheel is forced back in the opposite direction.

15 The operation of the coin controlled device is as follows:

When the power lines 12, 13 are connected to a suitable source of power, such as the alternating current lighting circuit, the constant speed 20 clock motor 17 will operate continuously and rotate continuously the lantern wheel 49 and dial 56. When the dial 56 has its camming flange 57 moved into position to engage the 25 switch lever 58, the switch push button 18 will be actuated to open the switch to effect defrosting.

The length of this defrosting period is covered by the arcuate length of the flange 57, and when the flange 57 has passed the hump 90 the switch 30 lever 58 will again permit switch 14, 15 to close, the closing being effected by the switch spring 19.

At any time the operator may push inward on the knob 68 and turn the knob to cause lever 65 to rotate the dial 56 for the purpose of shortening the defrosting period or setting the defrosting dial at any desired point. The defrosting is ordinarily accomplished every twenty-four hours, two hours being used in the defrosting.

The normal position of the dial plate 86 when 40 there are no coins deposited is with its camming flange 83 in the uppermost position, engaging the switch lever 58 and opening the switch. At this position of the mechanism the spring 83 is under a tension and tends to rotate the dial 86 in a clockwise direction. When a coin is deposited in the coin chute 34 it stops at the shoulder 41, engaging the end 37 of the lever 38. The operator is then required to push the actuating device 30 downward, which causes the coin 45 36 to pass the shoulder 41 and actuates lever 38 to cause the pawl 43 to permit escapement of one tooth on the ratchet wheel 8 and permit the ratchet wheel and dial 86 to register one coin by moving one step in a clockwise direction. For 50 every coin deposited the ratchet wheel 81 moves one step in a clockwise direction, and for every coin used up or period of refrigeration which has 55 elapsed, the ratchet wheel 81 is stepped backward in a counter-clockwise direction.

60 This backward stepping of the coin registering ratchet wheel 81 is accomplished by the action of the lantern wheel 49 on lever 73. When one of the pins on the lantern wheel 49 engages the camming surface 69 on bellcrank 70, this lever is rotated clockwise against its spring 75 to take a new position with respect to the ratchet wheel 76 and to engage another tooth of that ratchet wheel. When the pin passes the camming surface 69, then the bellcrank 70 is free to be moved 65 back to the position of Fig. 5 by its spring 75 and the pawl 74 rotates the ratchet wheel 76 one step in a clockwise direction. When there have been 70 coins deposited to be used up and the coin registry wheel 86 is in position to register any of these 75 coins, then the ratchet wheel 76 is adapted to ro-

tate ratchet wheel 81 one step for each flange 79 on ratchet wheel 76. Of course, if the coins have all been used up, then the space 87 of the ratchet wheel 81 is adjacent the ratchet wheel 76 and the tooth flanges 79 cannot rotate ratchet wheel 81, 5 because there are no teeth there on the ratchet wheel 81 to be engaged by the flanges 79.

The present device is adapted to be adjusted to control the operation of a refrigerator or other device at rates of from ten cents per day to 10 \$6 a day when twenty-four holes are used in the lantern wheel for pins and ten teeth are used on the ratchet wheel 76, and the coin used is a twenty-five cent coin. For example, the lantern wheel 49 rotates once in twenty-four hours. Assuming 15 that a twenty-five cent coin is used and two pins are used upon the lantern wheel and every fifth tooth on the drive ratchet 76 is flanged, it can readily be shown that the cost of operation of the refrigerator would then be at the rate of ten 20 cents per day.

The lantern wheel would rotate once every twenty-four hours and would actuate bellcrank 70 once every twelve hours. It would take five 25 actuations of the drive ratchet 76, however, to produce one step of movement of the coin registering ratchet 81 because only every fifth tooth of the drive ratchet 76 is flanged. Therefore, it would take five times twelve hours, or sixty hours 30 of operation of the lantern wheel before the coin registry ratchet is stepped back one step or before one coin is used up.

It should be understood that any number of 35 teeth may be used in the various ratchets, and I prefer to use a thirty tooth ratchet wheel for the coin registry ratchet, which leaves approximately twenty teeth for the purpose of operation and enables the device to register twenty coins.

It will thus be observed that by using only one type of gear, such as the lantern wheel, I am enabled to adjust my device for various rates of cost of operation. This makes the device capable of very economical manufacture because it is not necessary to keep so many types of gears in stock to meet the needs of the various manufacturers who will use these devices upon their refrigerators and other appliances. All that it is necessary to do is to regulate the number of pins which are placed in the lantern wheel and the number of flanges on the drive ratchet, and various 40 different results can be accomplished, such as exemplified in the table above. Of course, different rates of cost per day and different periods of time may be used by using different numbers of teeth on the ratchets and gears, and I do not wish 45 to be limited to the numerical relations shown because these gears and ratchet wheels are merely exemplary of one form of the invention.

While I have illustrated a preferred embodiment of my invention, many modifications may 50 be made without departing from the spirit of the invention, and I do not wish to be limited to the precise details of construction set forth, but desire to avail myself of all changes within the scope 55 of the appended claims.

Having thus described my invention, what I 60 claim as new and desire to secure by Letters Patent of the United States, is:

1. In combination, an electrically actuated power device, a supply circuit therefor and a 65 switch in said circuit, mechanism for controlling said switch, comprising a rotatable ratchet wheel, an escapement pawl for controlling the movement of said ratchet wheel in one direction, a spring for urging said wheel in said direction, a 70

timing device, a timing wheel having a plurality of pins actuated by said timing device, a second ratchet wheel rotatable oppositely to said first ratchet wheel under the influence of said spring, and a pawl adapted to be actuated by said pins for stepping said ratchet wheel in said opposite direction, said switch means being controlled by said first ratchet wheel, and said pawl acting upon said second ratchet wheel, the latter having lugs for engaging the teeth of said first mentioned ratchet wheel.

2. In combination, an electrically actuated power device, a supply circuit therefor and a switch in said circuit, mechanism for controlling said switch, comprising a rotatable ratchet wheel, an escapement pawl for controlling the movement of said ratchet wheel in one direction, a spring for urging said wheel in said direction, a timing device, a timing wheel having a plurality of pins actuated by said timing device, and a pawl adapted to be actuated by said pins for stepping said ratchet wheel in the opposite direction, said switch means being controlled by said ratchet wheel, said switch means also being controlled by said timing wheel whereby the switch may be periodically opened.

3. In combination, a registering member rotatable in either direction and yieldingly urged in one direction, an escapement pawl controlling the movement of said member in said one direction, a timing device for causing periodic movement of said member in the opposite direction, said timing device running continuously, switch means controlled by said member and adapted to be actuated to open position when said member reaches a predetermined position in its rotation in said opposite direction, and means operable independently of said member for actuating said switch to open position.

4. In combination, a registering member rotatable in either direction, means for rotating said member in one direction, a timing device for causing periodic movement of the registering member in the opposite direction, said timing device running continuously, and switch means controlled by said registering member and adapted to be actuated to open position when said member reaches a predetermined position in its rotation in said opposite direction, and means optionally operable independently of said member for actuating said switch to open position, said last means normally being actuated by the timing de-

vice whereby opening of said switch is automatically accomplished at predetermined intervals.

5. In combination, a ratchet wheel with an escapement pawl, resilient means for urging said ratchet wheel in one direction, a switch actuating member controlled by said ratchet wheel, a timing means, a switch for controlling an electric appliance, said timing means being adapted to step said ratchet wheel in an opposite direction against the tension of said spring at intervals predetermined by said timing means, a lantern wheel continuously rotated by said timing means, pawl means for actuating said ratchet wheel against the tension of its spring, and camming means carried by said pawl and engaging shoulders carried by said lantern wheel, said lantern wheel having a multiplicity of apertures for receiving pins forming the shoulders for actuating said latter pawl and predetermining the time period of said controlling device.

6. In combination, a ratchet wheel rotatable in either direction, yielding means urging said wheel in one direction, an escapement pawl controlling rotation of said wheel in said one direction, a second ratchet wheel rotatable in the same direction as said first wheel under the influence of said yielding means, said second wheel having means cooperating with said first wheel for rotating the latter step by step in the opposite direction, a continuously driven timing member, means actuated by said member for periodically turning said second wheel, and a normally closed electric switch opened by said first wheel when the latter has been turned into predetermined position in opposition to said yielding means.

7. In combination, a ratchet wheel rotatable in either direction, yielding means urging said wheel in one direction, an escapement pawl controlling rotation of said wheel in said one direction, a second wheel rotatable in the same direction as said first wheel under the influence of said yielding means, said second wheel having means cooperating with said first wheel for rotating the latter step by step in the opposite direction, a continuously driven timing member, driving connections between said member and said second wheel, and a normally closed electric switch opened by said first wheel when the latter has been turned into predetermined position in opposition to said yielding means.

GEORGE H. NIEDERST.
